CABLE AND SEISMOMETER TRUCK

Clifford D. Dransfield and Darvin D. Shields, Dallas, and
Oswald Paxton, Plano, Tex., assignors to Atlantic Richfield Company, Philadelphia, Pa., a corporation of Pennsylvania

Continuation-in-part of design application Ser. No. 10,073, Jan. 8, 1968. This application Aug. 9, 1968, Ser. No. 13,352

Term of patent 14 years

Int. Cl. D12—09

U.S. Cl. D14—3

Fig. 1

Fig. 2

Fig. 3

*Fig. 4**Fig. 5*FIGURE 1 is a side elevational view of a cable and seismometer truck, embodying our design;

FIGURE 2 is a fragmentary perspective view thereof, showing the cover of one of the seismometer compartments;

FIGURE 3 is a fragmentary perspective view thereof, looking from one side of the truck to the other through the seismometer compartments at the rear of the truck, the covers being in raised position;

FIGURE 4 is a top planar view thereof, showing that it has an open bed; and

FIGURE 5 is a rear elevational view thereof.

The front elevation (not shown) is similar to FIGURE 5 except that the cab largely blocks the view of the bed.

The side opposite that shown in FIGURE 1 is a mirror image thereof.

The dominant features of our design reside in the portions shown in full lines.

This application is a continuation-in-part of copending application Ser. No. D.10,073 filed Jan. 8, 1968, now abandoned.

We claim:

The ornamental design for a cable and seismometer truck, substantially as shown and described.
